UNITED STATES PATENT OFFICE.

ALONZO SEDGWICK, OF POUGHKEEPSIE, ASSIGNOR, BY MESNE ASSIGNMENTS,
TO D. H. BURRELL & COMPANY, OF LITTLE FALLS, NEW YORK.

RULING-MACHINE.

SPECIFICATION forming part of Letters Patent No. 391,278, dated October 16, 1888.

Application filed June 2, 1887. Serial No. 240,055. (No model.)

To all whom it may concern:

Be it known that I, ALONZO SEDGWICK, of the city of Poughkeepsie, in the county of Dutchess and State of New York, have invented a new and useful Improvement in Ruling-Machines, of which the following is a specification.

This invention relates to that class of ruling-machines which are provided with thin revolving rings or disks, to which the ink is applied and whereby the lines are formed upon the paper, said ruling rings or disks operating in conjunction with rollers having supporting rings or collars, against which the paper rests in passing over the ruling-rings, and which are arranged opposite the spaces between the ruling-rings.

The object of this invention is to improve the construction of these supporting-rollers so that they can be produced at comparatively small expense, and so that their rings can be easily adjusted.

My invention consists to that end of the improvements which will be hereinafter fully described, and pointed out in the claims.

In the accompanying drawings, Figure 1 is a longitudinal sectional elevation of a ruling-machine provided with my improvements. Fig. 2 is a sectional elevation of a ruling-cylinder and a supporting-roller. Fig. 3 is a cross section of the supporting-roller in line *xx*, Fig. 2. Fig. 4 is a fragmentary elevation showing a modified construction of the supporting-cylinder. Fig. 5 is a cross section in line *xx*, Fig. 4.

Like letters of reference refer to like parts in the several figures.

A represents the frame of the machine, and *a* the feed-tapes which convey the paper to the machine.

B represents the lower ruling-cylinder, and *C* the supporting-roller arranged above the same.

D represents the lower ink-fountain; *d*, the ink-roller arranged in the same; and *E*, the intermediate roller, which transfers the ink from the ink-roller to the ruling-cylinder *B*.

F represents the upper ruling-cylinder, and *G* the supporting-roller arranged below the same.

H represents the upper ink-fountain; *h*, the ink-roller arranged in the same; and *I*, the in-

termediate roller, which transfers the ink from the ink-roller *h* to the upper ruling-cylinder, *F*.

K represents the receiving-table, upon which the sheets are delivered from the ruling mechanism.

The supporting-rollers *C* and *G* are each provided with rings *l*, which are detachably secured to the faces of these rollers. To this end the rings are constructed of elastic material, which permits them to be slipped in place on the rollers and holds them in position. These supporting-rings *l* are preferably constructed of soft rubber, in which case they are made endless, as represented in Figs. 2 and 3. The elastic character of these rings permits their edges to yield slightly as the paper passes between the supporting-rings and the ruling-disks, which stand opposite the spaces between said rings, and prevents the cutting or creasing of the paper when sufficient pressure is exerted by the ruling-disks to form a solid unbroken line. If desired, the rings *l* can be constructed of metal and split, as represented in Figs. 4 and 5. In this case the rings are turned out to a slightly smaller inner diameter than the outer surface of the roller, whereby the rings are caused to bind on the roller. The rings are arranged on the supporting-rollers so as to stand opposite the spaces between the ruling-rings *m* of the ruling-cylinders, as represented in Fig. 2. The rings *l* are easily adjusted on the rollers *C* and *G*, as the position of the ruling-rings may require, the latter being preferably permanently secured to their cylinders by soldering or otherwise.

By this means the supporting-rings can be arranged on their cylinder to correspond with the arrangement of the ruling-disks when the ruling-cylinder is removed and replaced by another in changing from one kind of work to another, thus enabling one supporting-roller to be used with a variety of ruling-cylinders. My improved construction of the supporting-rollers also permits the rings to be removed and to be replaced by wider or narrower rings when it becomes necessary to reduce or increase the width of the spaces between the rings as the particular kind of paper and the particular kind of ink used may render necessary in order to produce uniform and unbroken lines.

I claim as my invention—

1. The combination, in a ruling-machine, of a series of ruling devices arranged side by side, and a roller provided with elastic paper-supporting rings mounted upon the cylindrical surface of the roller and held by frictional contact thereon, whereby the rings can be adjusted laterally on the roller as the position of the ruling devices may require, substantially as set forth.
- 10 2. The combination, in a ruling-machine, of a series of ruling devices arranged side by side,

and a roller provided on its cylindrical surface with projecting rings of soft rubber held by frictional contact on the surface of the roller and separated by intervening open spaces, 15 substantially as set forth.

Witness my hand this 26th day of May, 1887.

ALONZO SEDGWICK.
